UNITED STATES PATENT OFFICE.

JOHN E. ENGRAM, OF EUFAULA, ALABAMA.

COTTON-CLEANER.

SPECIFICATION forming part of Letters Patent No. 268,209, dated November 28, 1882.

Application filed September 30, 1882. (No model.)

To all whom it may concern:

Be it known that I, JOHN EDWARD ENGRAM, a citizen of the United States, residing at Eu-
faula, in the county of Barbour and State of
Alabama, having invented a new and Im-
proved Cotton-Cleaner, of which the following
is a specification.

My invention relates to that class of cotton-
cleaners used as an accessory to the common
gin to clean the cotton of dust, trash, and dirt
immediately after the cotton passes the brush
which takes it from the gin-saws and it con-
sists in the construction and combination of
parts hereinafter fully described and claimed,
reference being had to the accompanying
drawings, in which—

Figure 1 is a side elevation of a cotton-gin.
Fig. 2 is a longitudinal vertical sectional ele-
vation of my invention, showing its relation
with a cotton-gin. Fig. 3 is a detail view.

A represents the saws, and B the brush,
commonly used in cotton-gins.

As my invention does not relate to the gin
proper, I make no description thereof; but my
device is attached to any kind of a cotton-gin
which uses a rotary brush to clean the cotton
from the saw-teeth and to throw or blow it
into the lint-room or condenser.

C is an inclined bed made up of pivoted
slats c, like a Venetian blind. These slats
c may be given any desired pitch by means
of the connecting-rod a, linked by small staples
to each slat. They usually stand nearly verti-
cal, about one-half or three-quarters of an inch
apart, their upper faces being given about the
incline of their general plane.

b represent two independently-pivoted slats
or bars, in each of which a series of wires, d, is
fixed, the wires being about a half-inch apart
along the slats b, and the slats are slanted to
point the wires out of the gin-flue in the direc-
tion which the cotton is blown by the gin.

e is an upper pivoted bar or slat, similarly
provided with wires f, pointing in a downward
plane out of the flue. The wires are of a size
and material to spring under pressure and con-
tinually restore themselves to their normal
position when the pressure is removed. Their

use is to interrupt the cotton in its passage
out of the gin, and the cotton being thrown 50
forcibly against them to jar the dust and dirt
out. To this end the lower set of wires first
receives the flying cotton and deflects it to the
upper wires, and they in turn deflect it to the
outer tier of wires, thus thoroughly beating it 55
in its escape from the gin. The dust and dirt,
being much heavier than the cotton, espe-
cially after the cotton is loosened by the gin, fall
to the bottom when so jarred out; and the
cotton, gathering continually against the wires, 60
causes an eddy behind them in the current of
air, which leaves the dirt more free to settle
there than in the direct current. The spaces
between slats c are to allow the dirt to fall out
of the machine, and they may be regulated to 65
any desired width by changing the pitch of
the slats. The bars holding the wires may
also be set to any desired angle to offer more
or less resistance to the flying cotton. The
slats c and bars b e are pivoted so closely as to 70
stay in any position in which they are set.

The use of my invention renders the cotton
cleaner, and consequently more valuable, with-
out any extra cost in the process of gin-
ning and cleaning over the common cost of clean- 75
ing.

What I claim as my invention, and wish to
secure by Letters Patent, is—

1. The combination, with a cotton-gin flue
having openings through its bottom, of de- 80
flecting-wires secured within the flue, sub-
stantially as specified.

2. The combination, with a cotton-gin flue
having openings through its bottom, of adjust- 85
ably-pivoted bars or slats provided with de-
flecting-wires, substantially as described.

3. The combination, with a cotton-gin flue
provided with the deflecting-wires described,
of adjustably-pivoted slats in its bottom, hav- 90
ing openings between them, substantially as
specified.

JOHN EDWARD ENGRAM.
